US00D797044S

(12) **United States Design Patent** (10) **Patent No.:** **US D797,044 S**
Miller et al. (45) **Date of Patent:** **** Sep. 12, 2017**

(54) **PORTABLE POWER CHARGER WITH AC AND DC CHARGING CAPABILITY**

(71) Applicant: **Halo International SEZC Ltd.**, Georgetown, Grand Cayman (KY)

(72) Inventors: **Garold C. Miller**, Glastonbury, CT (US); **Nathan Daniel Weinstein**, Glastonbury, CT (US)

(73) Assignee: **HALO INTERNATIONAL SEZC LTD.**, Georgetown (KY)

(**) Term: **15 Years**

(21) Appl. No.: **29/566,458**

(22) Filed: **May 31, 2016**

(51) LOC (10) Cl. **13-02**

(52) U.S. Cl.

USPC **D13/108**

CLAIM

The ornamental design for a portable power charger with AC and DC charging capability, substantially as shown and described.

DESCRIPTION

FIG. 1 is a front, top perspective view of a portable power charger with AC and DC charging capability showing our new design;

FIG. 2 is a front view thereof;

FIG. 3 is a back view thereof;

FIG. 4 is a left-hand side view thereof;

FIG. 5 is a right-hand side view thereof;

FIG. 6 is a top view thereof; and,

FIG. 7 is a bottom view thereof.

The broken lines present in the figures are included for the purpose of illustrating portions of the article that form no part of the claimed design.

1 Claim, 4 Drawing Sheets
